UNITED STATES PATENT OFFICE

FRED J. MARTY AND HOWARD D. YODER, OF DETROIT, MICHIGAN, ASSIGNORS TO PENBERTHY INJECTOR COMPANY, OF DETROIT, MICHIGAN, A CORPORATION OF MICHIGAN

INJECTOR

Application filed February 8, 1929. Serial No. 338,350.

This invention relates to injectors and particularly to single tube injectors of the automatic overflow type which are arranged to automatically reestablish the jet after any interruption of water supply during the working cycles of the injectors.

The automatic reestablishing feature resides in the provision of large relief space or openings between the suction and delivery tubes so that before mixture of steam and water has reached proper proportions the improperly mixed jet can escape through the overflow valve and thence to the atmosphere. When the steam and water have reached proper proportions the jet overcomes the boiler pressure and rushes through the delivery jet tube without spillage thus creating a vacuum in the injector body and thus closing the overflow valve and reducing the relief space to working range.

The pressure in the delivery chamber set up by the established jet acts to move the sliding delivery tube into such position as to cut down the large starting relief space to working range so that there is no discharge to the atmosphere and no spillage from the delivery tube after the jet has been established due to high internal pressure or high internal temperature.

The provision of the large starting relief space may be accomplished in various ways. There are shown herein two such ways of establishing a large starting relief space in connection with single tube injectors. One form consists in forming a plurality of spill holes in the sliding delivery tube and the other consists in the utilization of a sliding delivery tube without any spill holes which is moved into working position by the pressure in the delivery chamber.

The spill holes in the delivery tube are required for automatic starting but are not efficient as to maximum range of operation after the jet has been established as internal pressure in the delivery tube, due to high steam pressure or high water temperature as the case may be, causes discharge of some water through the spill holes which eventually escapes through the overflow so that such escape will admit some air to the combining

chamber thereby affecting the vacuum established in this chamber. It is therefore desirable to provide means for reducing the large starting area between the sliding delivery tube and the suction jet where a tube without spill holes is employed or shutting off escape from the spill holes after the jet has been established to allow operation of the injector through a wide range.

An object of the invention is to provide an injector in which spillage is allowed for starting and eliminated after the jet is established.

Another object of the invention is to provide an injector in which the elimination of spillage effect is accomplished by the action of the jet.

A further object of the invention is to provide an injector with a large starting space or area between the suction and delivery tubes for starting purposes and reducing said space or area after the jet is established by building up pressure in the delivery chamber wherefore the action of the jet itself serves to reduce such starting space.

A still further object of the invention is to provide an injector in which large spillage is provided for starting purposes and which spillage is stopped after establishment of the jet by building up pressure in the delivery chamber wherefore the action of the jet itself serves to reduce such starting space.

A yet further object of the invention is to provide an injector with a sliding delivery tube and double acting valved relief for the combining and delivery chambers.

A yet further object of the invention is to provide an injector having a sliding delivery tube which requires no packing.

A still further object of the invention is to provide a single tube automatic injector of the automatic overflow type arranged to automatically reestablish itself after interruption of water supply during its working cycle which injector is economical to manufacture and efficient in operation over a wide range.

The above, other and further objects of the invention will be apparent from the following description, accompanying drawings and appended claims.

This invention in one form is illustrated in the accompanying drawings and the views thereof are as follows:

Figure 1 is a vertical central section through an injector of the single tube type shown with double acting valves in the overflow chamber and embodying this invention.

Figure 2 is a section taken on line II—II of Figure 1.

Figure 3 is a central vertical sectional view through an injector embodying this invention and showing a single valve for the overflow.

Figure 4 is a fragmental central sectional view through an injector showing a modified delivery tube in connection with a single overflow valve, which type of delivery tube may be used in an injector having either a single overflow valve or the double overflow valve shown in the other figures.

Figure 5 is a central vertical section through an injector of the autopositive type showing a sliding delivery tube and arranged to embody the present invention.

The injector illustrated in Figure 1 comprises a body casting 1 formed with partitions defining a water and steam chamber A, a combining chamber B, a delivery chamber C and an overflow chamber D. The casting is provided also with a steam inlet 2, a water inlet 3, a boiler discharge outlet 4 and an overflow outlet 5. A steam jet 6 is threaded or otherwise arranged in the steam inlet 2 which jet projects into the chamber A.

The partition 7 between the chambers A and B is centrally apertured and a suction jet 8 is threaded into the aperture through the partition 7 which jet is arranged to project each side of said partition and is provided with its receiving end 9 flared and larger in diameter than the discharge end of the steam jet 6. The suction jet tube 8 has a flange 10 about its outer surface to seat against the underside of the partition 7 and thus make the joint through the partition steam and watertight.

A brass housing 11 having cylindrical side walls and a transverse end 12 is arranged in the lower part of the body casting 1. The body casting 1 is provided near its lower end with a cylindrical wall 13 into the space defined by which wall extends the housing 11. The housing 11 has an end flange 14 which bears against the body 1 adjacent said opening 13. A washer 15 is interposed between the outer end of the housing 11 and a spider 16 which is retained against said washer to hold the housing in position by a cap nut 17 threaded at 18 into an opening in the lower end of the body casting 1. The upper wall 12 of the housing 11 is centrally apertured at 19 with the upper portion of the aperture flared outwardly.

A bushing or wall member 20 is secured on top of the housing 11 and is provided with

an upper ring 21 for receiving the inner end of the suction jet tube 8.

A sliding delivering tube 22 is movably arranged within the housing 11 and as shown in Figure 1 is in lowermost position. The upper end of the tube 22 when in the lowermost position is arranged to project a slight distance beyond the top wall 12 of the housing 11 while the lower end of said tube extends downwardly below the washer 15 and into the delivery chamber C which is formed in the nut 17. The delivery tube 22 has a centrally bored portion the receiving end of which converges a slight distance forming the portion 23 then there is an intermediate substantially cylindrical portion with a diverging end portion 25. The delivery tube 22 is provided as shown in Figure 1 with a plurality of spill holes 26 extending laterally through the wall of said tube to afford communication between the interior and exterior of said tube. The lower end of the housing 11 provides a bearing for the lower end of the delivery tube 22 as the same is moved in action as hereinafter more fully explained. The delivery tube 22 is provided also with an outwardly extending annular ring 27 near its upper end which ring serves as a valve to seat against the underside of the opening 19 through the upper wall 12 of the housing 11 when the delivery tube 22 is moved to its uppermost position to seal the opening 19.

The uppermost position of delivery tube 22 is shown in dotted lines in Figure 1.

The delivery tube 22 is provided with laterally disposed openings 28 near its upper end and also with axially formed ribs 29 on the outside thereof extending upwardly from the valve 27 to the upper end of the tube 22 for the purpose of allowing the passage of water through the opening 19 in the housing 11 for escape through the overflow chamber as hereinafter more fully explained.

The body casting 1 of the injector has a lateral portion 30 forming a part of the overflow chamber D and providing communication between delivery chamber C and the overflow chamber D. The wall 31 of the injector between the combining chamber B and the overflow chamber D is provided with a cylindrical opening 32. A valve 33 having a cylindrical top is arranged to seat against said opening 32 and close the same under certain conditions. The valve 33 is provided with axially extending guide wings 34 for controlling the movement of the valve in operation.

A threaded nipple 35 is threaded into said chamber 30 outwardly of the valve 33. Said nipple 35 has a central opening 36 therein in axial alignment with the opening 32 in the wall 31 but of smaller diameter.

A valve 58 is arranged to seat against the outer surface of said nipple 35 and close the opening 36 therethrough under certain con-

ditions. This valve 58 has guide wings 37 for guiding said valve in its movements. The outer surface of the valve 58 is provided with a projection 38 for limiting outward movement of said valve. A hollow cap member 39 is threaded in the end of the extension member 30 of the body casting 1. The extension 30 is formed with a passageway 40 communicating with the delivery chamber C and 10 the interior of the cap member 39.

The overflow chamber D has an outlet 41 to which may be connected any kind of waste pipe as desired.

Suitable steam and water pipes are connected to the steam inlet 2, the water inlet 3 and to the boiler outlet 4 for communication with the boiler in a manner well understood.

The injector shown in Figure 3 as far as the working parts thereof are concerned is exactly the same as that described with reference to Figure 1 except that instead of the double outlet valves between the combining chamber B and the overflow chamber D a single valve 42 is provided to seat in valve 25 seat 43 formed in one of the side walls of the body of the injector. The valve 42 is carried by an arm 44 pivoted at 45 to the casting and arranged to have swinging movement about the pivot 45. There is no communicating passage between the delivery chamber C and the overflow chamber D of the form of injector shown in Figure 3.

The arrangement shown in Figure 4 includes a housing 46 similar to housing 11 of Figure 1 in which is slidably mounted a delivery tube 47. The housing 46 is provided intermediate its length with annular valve seat 48 against which a ring valve 49 on the delivery tube 47 engages to seal communication between the delivery chamber C and the combining chamber B when the tube is in raised or fully operating position. The valve 49 is arranged to seat against the underside of the valve seat 48 as said tube is raised.

The delivery tube shown in Figure 4 does not have any spill openings of any kind except that near its upper end it is provided with diametrically opposite openings 50, 51.

The housing 46 is secured in the injector 50 body casting by means of a nut 52 screwed into the lower end of said casting which nut has an inwardly extending skirt 53 provided with lateral openings 54 the upper end of which skirt bears against a guide bushing 55 55 which in turn rests against the underside or inner end of the housing 46. The bushing 55 may be provided with overflow ports 56 if desired.

It will be observed that the sliding delivery tube of this invention is arranged to be sealed with respect to the housing in which it slides in a manner to require no packing whatsoever.

The operation of the injector shown in Figure 1 is as follows. Steam is admitted

through the steam jet 6 and passes through suction tube 8 drawing with it water admitted through water inlet 3. The passage of steam through the chamber A creates a vacuum in said chamber for drawing in the water. The water passes through the suction jet 8 into the combining chamber B where the water condenses in the jet proper. The pressure of the water in the chamber B opens overflow valve 33 which in turn opens 75 outer valve 31 so that the water and steam in improper mixture in the combining chamber B may escape to the overflow until such time as the jet is established.

A partial vacuum is created in the combining chamber B by the velocity of the jet which aids in directing the incoming mixture of steam and water into the delivery tube 22 which is in the lowermost or full line position of Figure 1. Some water and steam 80 will pass through the delivery tube 22 at high velocity the water more fully condensing the steam and reducing its volume. This jet then passes into the delivery chamber C where until it is properly established 85 for flow into the boiler passes upwardly through the passage 40 against the outer valve 58 tending to close the same. Such water as does not enter the delivery tube will pass to the overflow chamber D through 90 the valve opening 32 and this state of affairs will continue until the jet is established.

Establishment of the jet reduces the pressure in the combining chamber B thus allowing valve 33 to move towards its seat. 100 Establishment of the jet increases the pressure in delivery chamber C which pressure is transmitted through the passageway 40 to the outer valve 58 and because of its large area closes said valve so that the pressure in the delivery chamber C is then built up to 105 direct the jet into the boiler against the boiler pressure. Establishment of the jet as before stated reduces the pressure in the combining chamber B allowing valve 33 to 110 close. This condition remains as long as the jet is fully established and as long as the water supply continues.

Should for any reason the water supply be discontinued then the pressure in delivery chamber C will fall, also the delivery tube 22 which in the meantime has been raised by the pressure in the delivery chamber C to close valve 27 against its seat 19, thereby re-establishing the starting area or space between the suction jet tube 8 and the receiving end of the delivery tube 22. The jet is re-established again in the manner before described.

The spill holes 26 in the delivery tube 22 receive the discharge through the same due to any internal pressure in the delivery tube where steam is employed or high temperature when hot water is employed. The internal pressure would cause an outflow of water 125

until the space within the housing 11 between it and the delivery tube were filled whereupon the spill holes 26 would be sealed by this pressure thus preventing the further escape of any water. Such arrangement permits the use of this injector with very high steam pressure or with very high temperature when hot water is employed.

The operation of the forms of the invention shown in Figures 3 and 4 is similar to that described with respect to Figure 1 except that with reference to Figure 3 the pressure in the combining chamber B will immediately open overflow valve 42 allowing escape to the atmosphere of such overflow water until such time that the jet is established. Establishment of the jet raises the delivery tube 22 to seal the valve 27 against its seat 19 thus placing the delivery tube in communication with the suction jet 8. Such state of affairs creates a vacuum in the combining chamber B allowing the valve 42 to close.

Operation of the injector shown in Figure 5 is similar to that described with reference to Figure 3 except that there are no spill holes in the delivery tube 47 so that there of course would then be no escape from said tube due to internal pressure. The housing 46 of the form shown in Figure 4 is provided with openings 57 to allow passage between chambers C and B.

The form of the injector shown in Figure 5 comprises a casting 59 having a steam inlet 60, water inlet 61, boiler connection 62 and overflow 63. The casting 59 is formed to provide a steam chamber E, a water chamber F, a combining chamber G, a delivery chamber H, and overflow chamber I.

A steam jet 64 is arranged in the injector and communicates between the steam chamber E and the water chamber F. A suction jet 65 is removably retained in the wall 66 of the injector between the water chamber F and the combining chamber G, which jet projects into each of these chambers. A sliding delivery tube 67 is supported within a housing 68 secured in the injector casing 59, and has limited sliding movement axially in said housing. The delivery tube 67 is provided with a collar 69 which is operable within a chamber J formed in the housing 68 by a partition 70 and a guide bushing 71 in the end of the housing. The collar 69 on the delivery jet tube 67 seats against the ring 70 when the delivery tube is forced outwardly, that is, into the full line position of Figure 5 by the pressure in the delivery chamber H.

A wall 72 of the overflow chamber I is provided with an opening 73 within which is axially movable a valve 74, the valve head of which seats against the outer end of the opening and moves within the overflow 63.

The valve is provided with a plurality of guide wings 75.

A nipple 76 communicates with the other wall of the overflow outlet 63 and carries another valve 77 of the same character as valve 74, but with a smaller head. This valve also is provided with guide wings 78. A hollow nut 79 is threaded into the injector casing to provide a closure forming a chamber K outwardly of the valve 77. The cap 79 is provided with a stop 80 for limiting the outward movement of the valve 77. The valves 74 and 77 are so arranged that movement of one will cause the movement of the other in the same direction.

The injector casting is provided with a communicating opening 81 between the delivery chamber H and the chamber K.

The housing 68 is provided with lateral openings 82 and the guide bushing 71 is provided with axial openings 83.

The operation of the injector of Figure 5 is similar to that of Figure 1 except that there is not relative movement between the valves 74 and 77 in the outlet chamber I.

The injector of Figure 5 is arranged to be horizontally disposed, that is, with the steam jet 64, the suction jet 65 and the sliding delivery tube 67 disposed on a horizontal axis rather than a vertical axis as shown in the other figures of the drawings.

It will be observed that by this invention a very large starting space or area is provided between the suction jet 8 and the delivery tube. Such space is too large of course for efficient operation of the injector after the jet is established. The provision of the sliding delivery tube makes possible the reduction of this space to operating range when the jet has been established the tube being moved by the jet itself when fully established. Furthermore, the provision of the sliding jet tube seals the spill openings when the same are employed so as to prevent internal pressure within said tube from escaping and passing to the overflow which escape of course would open the overflow valves admitting air to the combining chamber thus reducing the vacuum therein and reducing the range through which the injector would be operatively efficient.

The spill holes are desirable for the injector to reestablish the jet automatically starting the injector when the same has been stopped, but are undesirable for continuous operation of the jet. The injector must have sufficient relief space to automatically start so that before proper mixture of steam and water has been reached the improperly mixed jets can escape through the overflow valve to the atmosphere.

The combination of the sliding delivery tube and the double acting valves as set forth in Figure 1 proves very efficient in automatic operation of an injector of the automatic

overflow type comprising a single tube. The sliding delivery tube also lends itself effectively in injectors such as shown in Figures 3 and 4 of the drawings.

5 The arrangement of Figure 1 makes possible relief in the combining chamber and in the delivery chamber during the time that the jet is forming so that all excess water will be discharged through the overflow to the atmosphere. The arrangement of the valves 10 33 and 58 is such that the same move readily in response to pressure within the injector and movement of one will affect movement of the other in the same direction.

15 The form of the invention illustrated show the delivery tube as being slidable or movable. It is within the contemplation of this invention to make the delivery or combining tube in sections and slide or move all or some 20 of the sections to carry out the idea of the large relief space for starting which is automatically reduced to working range.

This invention has been described more or 25 less precisely herein yet it is to be understood that changes may be made in the arrangement and proportion of parts and that equivalents may be substituted all without departing from the spirit and scope of the invention.

The invention is claimed as follows:

30 1. An injector having a sliding delivery tube, said tube having spill holes therein, a housing surrounding said tube with the inlet end of said tube projecting through said housing, and a valve on said tube arranged to seal the space between said tube and said housing 35 when said tube is moved by pressure created by the established jet.

2. An injector having a sliding delivery tube, said tube having spill holes therein, a 40 housing surrounding that portion of the tube containing said holes and having an opening therein through which extends the inlet end of said tube, said tube being provided with passages lengthwise thereof for allowing 45 spillage of water discharged through said holes outwardly of said housing, and a ring on said tube arranged to seal said space and prevent spillage therethrough when said tube is raised by the pressure created by the 50 established jet.

3. An injector of the automatic open overflow type comprising a suction tube and a sliding delivery tube, a housing surrounding said delivery tube, said housing having an 55 opening through which the inlet end of said tube extends, a valve carried by said tube, said valve arranged to cooperate with said housing for preventing passage of water when said valve is in engagement with said 60 housing, said delivery tube having a plurality of spill holes therein arranged to discharge within said housing, said tube arranged on starting of the injector to lie with its valve out of engagement with said housing and on establishment of the jet to be

65 moved with said valve in engagement with said housing to seal escape therefrom, said tube being moved into sealing position by the pressure created by the established jet.

4. An injector having a suction tube, a sliding delivery tube movable towards and away from said suction tube, a housing about said delivery tube and with respect to which said delivery tube slides, said housing having a spillage opening therein, said delivery tube 70 having a valve portion for closing said spillage opening under certain conditions, said delivery tube being positioned away from said suction tube for providing spillage space 75 between said tube for starting said injector and movable by the pressure created by the established jet for closing said spillage space between said tubes, and also for closing said spillage opening in said housing.

5. An injector having a suction tube, a sliding delivery tube movable towards and away from said suction tube, a housing about 80 said delivery tube, said delivery tube arranged for sliding movement with respect to said housing, said housing having a spillage 85 opening therein, said delivery tube having a valve portion for closing said spillage opening under certain conditions, said delivery tube being positioned away from said suction tube for providing spillage space 90 between said tubes for starting said injector, an overflow valve opened by pressure of the water spilled between said tubes, said injector having a passage between the delivery chamber and the overflow valve whereby pressure in 95 said delivery chamber becomes effective to close said valve against said pressure as the jet is established, and said delivery tube being movable by the pressure created by the established jet for closing the spillage space 100 between said tubes and also for closing the spillage opening in said housing.

In testimony whereof, we have hereunto 105 subscribed our names at Detroit, Wayne County, Michigan.
